UNITED STATES PATENT OFFICE.

SHOHÉ TANAKA, OF AWAJI, JAPAN.

TRANSPOSING KEY-BOARD.

SPECIFICATION forming part of Letters Patent No. 403,306, dated May 14, 1889.

Application filed May 14, 1888. Serial No. 273,902. (No model.)

To all whom it may concern:

Be it known that I, SHOHÉ TANAKA, of Awaji, Japan, have invented certain new and useful Improvements in Pianos, of which the following is a specification, reference being had to the accompanying drawings, which form part of this specification, and in which similar letters of reference denote the same parts.

10 The invention relates to that kind of pianos in which a transposition of a piece of music from one key to another is effected by shifting the key-board of the piano in the horizontal plane, so that a given key is made to strike any string desired. By this means piano-forte playing can be simplified in such a way that a piece written in any key, after being transposed into another key—say the key of C—can be played with the keys belonging to the C-key by shifting the position of the key-board. A hearer will not be able to tell the difference of playing, and accordingly the exercising in piano-forte playing will be restricted to one major and one minor 15 key instead of twelve. As in certain compositions, however, modulations occur—*i. e.*, the shifting of the tune from one key to another while playing—it is necessary to have a means of effecting the displacement of the key-board 20 in such an easy and convenient manner that little or no interruption in playing will be perceptible.

25 All the arrangements used or tried heretofore, to my knowledge, for mechanical transposition do not satisfy the above condition, as they are too inconvenient and cumbersome in handling, and require so much time to be set to its proper position, that the playing must be stopped for some time whenever such 30 change of key is desired.

35 The object of the present invention is to overcome these difficulties in a simple and effective manner.

40 The invention consists in the details of improvement and the combinations of parts, that are more fully hereinafter set forth.

In the accompanying drawings, Figure 1 is a partial front view of the key-board and the front wall of an upright piano. Fig. 2 is a 45 vertical transverse section of the upper portion of a piano. Fig. 3 is a detail sectional

plan view of the transposing mechanism. Fig. 4 is a detail plan view showing the transposing-lever; and Fig. 5 is a front view of part of the key-board and transposing mechanism of a piano, other parts being in section. 55

Within the piano-casing A is a lever, *y*, which turns at one end on a stud, *b*, fastened to a bar, *b'*, within the piano-casing. The lever *y* carries a toothed sector, *c*, that gears with a rack, *d*, on a bar, *d'*, of the frame *e* of the key-board. The frame *e* rests upon rollers *r*, journaled in the key-board case, which is for a space of, say, seven white keys wider than the frame *e*, thus permitting the key-board frame *e* to be moved longitudinally for a full octave. 60

On the free end of the lever *y* is pivoted a stem or crank, *o*, that passes through a horizontal slot in the front wall, *a*, of the casing. 70

k is a knob on the outer end of the stem *o*, or the lever *y* could pass through the wall *a* and carry the knob *k*. When the knob *k* of the transposing-lever *y* is moved to the right or the left, the key-board will thereby be 75 shifted in the same direction.

As each single hammer-action normally rests with its foot *m* upon the felt *n* of its key-beam *n'*, and prevents a sidewise movement of the key-board *e*, the feet *m* of all the hammers should be simultaneously lifted out of their place to permit the shifting of the key-board. This is accomplished as follows: Upon a rock-shaft, *i*, extending from one side of the piano-case to the other and above the 80 lever *y* are secured arms *t*, only one of which is shown. A cross-bar, *g*, is secured to these arms, which cross-bar is below all the free ends of the wings *h*, each of which wings is connected to one foot *m*. When the shaft *i* 85 is rocked, the bar *g* will be raised by the arms *t*, and thereby the wings *h* raised, which wings then lift the feet *m* from the key-beams *n'*, and permit the key-frame *e* to be moved sidewise. 90

The shaft *i* is rocked at the proper time as follows: On said shaft *i* a lever, *l*, is mounted, (see Figs. 2 and 3,) the front part of which is widened to nearly the extent of the sector *c*, and shaped like a circular sector, with its 95 center in the stud *b*. The stem *o* of the lever *y*, which stem is permitted a slight up-and-

down motion, carries a vertical arm, *q*. The arm *q* carries upon a horizontal inwardly-extending stud, *s*², a roller, *s*, that contacts the upper portion of the lever *l*. By a spring, *f*, or springs, on the shaft *i*, and which bears at one end against the bar *b*', or elsewhere, the lever *l* is normally kept pressed upward. Therefore the roller *s* and also the stem *o* of the lever *y* are drawn up with said lever. The 10 slot of the front wall, *a*, through which the stem *o* passes, is provided in its upper part with a number of recesses or indentations. Into these recesses the stem *o* of the lever *y*, armed with a friction-roller, *o*', (see Fig. 3,) is adapted to fit and to remain through the action of the spring *f*, thereby holding the key-frame in its proper position. The recesses or indentations may be marked, so that the position of the stem *o* in a recess 15 20 25 30 35 40 45 50 55

indicates the key in which a piece will be played. By pressing down the stem *o* out of an indentation the front end of the lever *l* is depressed, and accordingly the shaft *i* rocked, which, acting through the bar *g* and wings *h*, raises the feet *m* from the key-beams *n*². The key-board frame *e* is now free to be moved by turning the lever *y*. When the lever *y* is released, the stem *o* will rise and enter a recess or indentation. As the stem *o* rises, the shaft *i* turns back into its normal position, the cross-bar *g* sinks down, and the feet *m* come to rest upon the felts *n* of the key-beams. Further, by means of the spring *f*, the stem *o* is made to slip in the nearest indentation, and thereby the felt end of the key-beam *n*² will be automatically brought exactly under the feet *m* of the hammer-action, and thus correct any inaccuracies of setting on the part of the player.

The ends of the arms *t* are connected by links *u* with a board, *w*, extending across the piano-case and swinging round the shaft *v*, suitably supported in the case. The lower edge of the board *w* faces the upper edge of the end of the key-beams *n*². By depressing the stem *o* and raising the ends of the arms *t* the board *w* is turned in such way that its lower edge swings above the ends of the key-beams; but the board *w* cannot make this movement if one or more keys are depressed—that is, if the inner end, *x*, of one or more key-beams *n*² are raised—and if the board *w* cannot swing the stem *o* cannot be depressed. The depressed keys must be first allowed to resume their normal position. This device, as simple as it is, is therefore a safeguard

against an injury of the hammer-action in case of accidental depression of a key just before the displacement of the key-board. Moreover, it protects the mechanism, too, if during the shifting of the transposing-lever a key should be depressed, for in that case the board *w* is already swung over the ends *x* of the key-beams and does not allow them to rise. 60 65

It will be understood that this mechanism can be applied not only to upright pianos, upon which the description is based, but to other musical instruments—such, for instance, as organs, harmoniums, table-pianos, saloon-pianos, &c.—having key-boards, with corresponding change in the positions of several parts, if necessary. 70

Having now described my invention, what I claim is—

75

1. In a transposing device for pianos, the rack *d* and the key-board frame carrying the same, combined with the lever *y*, having a toothed sector, *c*, engaging said rack, and with the wall *a*, having notches in which the lever *y* can rest to retain the key-board, substantially as shown and described, and for the purpose set forth. 80

2. In a transposing device for pianos, the combination of the key-board that is movable sidewise and a lever, *y*, having a toothed sector, *c*, with the rack *d*, fastened to the key-board frame, and with means, substantially as described, for lifting the feet *m* from the felts *n* of the key-beams prior to the displacement of the key-board, as specified. 85 90

3. The combination of the movable key-board *e*, lever *y*, for actuating same, and means for retaining said lever, upright *q*, lever *l*, engaged thereby, shaft *i*, carrying said 95 lever, arms *t* on said lever, cross-bar *g* on said arms, springs *f*, wings *h*, and feet *m*, substantially as shown and described, and for the purpose set forth.

4. In a transposing device for pianos, the key-board adapted to be shifted, in combination with the swinging bar *w*, to prevent the rising of the key-beams, and with means, substantially as described, for actuating said bar *w*, substantially as shown and described, and for the purpose set forth. 100 105

This specification signed by me this 21st day of March, 1888.
